[57] CLAIM

The ornamental design for a golf cart, as shown and described.

DESCRIPTION

FIG. 1 is a front view of a golf cart showing my new design;

FIG. 2 is a rear view of the golf cart shown in FIG. 1, in an extended condition and ready to be pulled;

FIG. 3 is a side view of the golf cart shown in FIG. 1, but in a retracted condition, the other side view being identical thereof; and,

FIG. 4 is a top view of golf cart.
